LEG ORNAMENT

Ben Edward Arnold, Port Orchard, Wash.

Application June 29, 1951, Serial No. 15,721

Term of patent 14 years

(Cl. D7—1)

To all whom it may concern:

Be it known that I, Ben Edward Arnold, a citizen of the United States of America, residing at Port Orchard, in the county of Kitsap and State of Washington, have invented a new, original and ornamental Design for a Leg Ornament, of which the following is a specification, reference being had to the accompanying drawing, forming a part hereof.

The figure is a perspective view of a leg ornament showing my new design, the opposite side thereof being essentially the same in appearance as the side shown.

I claim:

The ornamental design for a leg ornament, as shown and described.

BEN EDWARD ARNOLD.
